(57) **CLAIM**

The ornamental design for a furniture leg protector, as shown and described.

DESCRIPTION

FIG. 1 is a perspective view of a furniture leg protector showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings illustrate portions of the furniture leg protector that form no part of the claimed design.

The claim is directed to shaded surfaces. Any unshaded surfaces shown in broken lines or between solid and broken lines form no part of the claimed design.
